UNITED STATES PATENT OFFICE.

EVERETT M. LOW, OF BROOKLYN, NEW YORK.

CHUTE-SPRING.

1,107,679.

Specification of Letters Patent. Patented Aug. 18, 1914.

Application filed February 20, 1911. Serial No. 603,821.

To all whom it may concern:

Be it known that I, EVERETT M. LOW, citizen of the United States, residing at Brooklyn, in the county of Kings and State 5 of New York, have invented certain new and useful Improvements in Chute-Springs, of which the following is a specification.

My invention relates to that class of devices known as chute springs, which form 10 an important element in the assembling mechanism of the linotype machine and the object of my invention is to provide a chute spring that will act more efficiently than the ones now in use, by avoiding transpositions in the assembled line of matrices and 15 space bands; by preventing the matrices from jumping out of the assembling elevator or choking up in the assembler and by avoiding the wear on the matrices incident 20 to an assembled matrix being struck by the one that follows it in the act of assembling. I attain these objects by the device illustrated in the accompanying drawings in which:

25 Figure 1, is an elevation of the chute spring and so much of the assembling mechanism as is necessary to show its connection therewith; Fig. 2, is a view of the chute spring looking in the direction of the arrow *y*, Fig. 1; Fig. 3, is a view of the matrix, showing the points where the matrices are damaged by the ones following in 30 the act of assembling; Fig. 4, is a view of the chute spring looking in the direction of the arrow *Z*, Fig. 2.

Similar letters refer to similar parts throughout the several views.

In Fig. 1, the assembler *a*, is shown with the glass front removed and the assembling 40 elevator *b*, is shown with the front part removed, the better to show the matrices in the assembling mechanism. The matrices descend the magazine plate *f* between the guides *c*, through the throat *d*, into the assembling elevator *b*, by the action of gravity 45 and the rapidly moving inclined belt *e*, after being released in the usual and well known manner from the magazine which is located above the magazine plate *f*, and the 50 guides *c*, only a part of which are shown. The matrices descend through the throat *d*, and as soon as the top *t*, of the matrix *S*, has passed the chute spring *A*, it is forced forward and downward to a vertical position 55 in the assembling elevator *b*, by the action of the rapidly revolving star wheel *h*,

which causes the matrix *S*, to take its place in the assembling line *i*. The space bands *j*, fall by gravity through the chute *k*, as they are released from the space band box 60 by the usual and well known means. The matrices and space bands are assembled with great rapidity and frequent transpositions of the matrices and space bands occur owing to the top *t*, of the matrix *S*, being retarded 65 in the act of assuming a vertical position, thus allowing the space band *j*, to drop before the matrix *S*, has moved far enough forward to be in advance of the descending space band and consequently the space band 70 *j*, is on the wrong side of the matrix *S*, or is transposed. The throat *d*, must be of such width as to allow the matrices to pass through freely but must not be wide enough to allow the matrices to assume a horizontal 75 position and jump out on the top of the assembling line and the downward extensions 5—5 of the chute spring *A*, must project far enough toward the assembling elevator *b*, to prevent the matrices from jumping upward and out of the assembling elevator *b*. The chute springs in use heretofore have the lower end bent at such an angle that it lies in a horizontal plane along the line *x*, *x*. As the top *t*, of the matrix *S*, 80 is forced by the star wheel *h*, outward after it passes below the throat plate *g*, it moves in a curve and should be free from retardation from the time it leaves its contact with the throat plate *g*, until it impinges against 85 the downward extensions 5—5 just above their points.

In the chute springs heretofore in use there is no concavity at 6, and the top *t*, of the matrix *S*, is retarded allowing the space 90 band *j*, to drop ahead instead of behind the matrix, causing a transposition. This retardation of the top *t*, of the matrix *S*, causes the lower end *p*, of the matrix to be thrown outward by the action of the star wheel *h*, causing the end *p*, of the matrix *S*, to strike the matrix *v*, in the assembling line at the points *r*, *r*, wearing away the wall of the matrix and causing burs on the type from the molten metal entering between the 100 matrices, where they are worn away. The free movement of the top *t*, of the matrix *S*, under the concavity 6, also prevents the matrix from being thrown out of the assembler by the retardation and sudden release of 105 the top *t*, of the matrix *S*, as is the case when the chute spring has no concavity 6.

In the chute springs heretofore in use a stop is riveted to the spring at 10, which holds the spring in place by impinging against a notch in the plate *f*, and preventing the spring from closing the throat *d*, adjustment is made by bending the spring and there is no independent adjustment for the throat *d*, and the lower part of the spring which forms the upper wall of the throat *d*, is a single piece and the prongs are straight and lie in a horizontal plane as indicated by the dotted line *x*, *x*.

The chute spring of my improved construction is formed of the member 1, and the member 2, secured to the member 1, at the upper end 3. The member 2, has two prongs 4—4, under which the top *t*, of the matrix *S*, passes, the space bands passing between the prongs 4—4. The lower end of the member 1, which forms the adjustable throat plate 8, is free below the point 3, and may be moved to or from the heel 7, of the prongs 4—4, in order to adjust the width of the throat *d*, without changing the position of the downward extensions 5—5, of the prongs 4—4, which should be set as far forward as possible without interfering with the passage of the assembling elevator when it is raised with the assembled line in the act of sending the line to the casting mechanism. The throat plate 8, is held normally against the member 2, by its tension and to move it away from the member 2, and hold it in its adjusted position the member 2, has the horn 9, which may be bent to throw the throat plate 8, away from the member 2, and hold it in any desired position to secure the proper width of the throat *d*. The throat plate 8, projects below the heel 7, of the prongs 4—4, forming the concavity 6, to allow the free passage of the top *t*, of the matrix *S*, as it moves outward under the action of the star wheel *h*. This concavity 6, could be secured without the use of the throat-plate 8, by cutting away the prongs 4—4, at the point 6, but I accomplish the same result by projecting the throat plate 8, below the prongs 4—4. The downward extensions 5—5, are in practice set even with or slightly in advance of the edge of the assembler plate *m*, and the downward extensions 5—5, project downward far enough to hold the top *t*, of the matrix *S*, from tilting outward and to press the matrix downward into the assembling elevator as it is forced outward by the action of the star wheel *h*.

The stop 10, is bent at a right angle at 11, and in the form of the letter *U*, at 12. It is secured to the member 1, by the clip 13, which allows a movement of the stop 10, in the direction of its length thus allowing the chute spring A, to be raised or lowered. This adjustment is made necessary by the narrow notch *n*, in the plate *f*, which admits but little movement.

The chute spring A, is held against the stop 10, by the tension of the member 1, the stop 10, serving to limit the movement of the chute spring toward the throat *d*.

The chute spring A, is secured to the machine at *O*, in the usual and well known manner, and as no change has been made in this part of the device, it has therefore not been shown in detail. The tension of the member 1, is just enough to hold the stop 10, against the side of the notch *n*, with a slight pressure which allows the chute spring to raise when large matrices pass through the throat *d*.

What I claim and desire to secure by Letters Patent is:

1. In a type bar machine having a magazine plate and a matrix chute, a chute spring arranged in juxtaposition to the matrix chute, embodying a throat plate for engaging the matrices as they pass through the throat, forwardly extending prongs arranged to prevent the matrices from jumping upwardly out of the line forming position, means for engaging the magazine plate of the machine to retain the prong member in position, and means for adjusting the relative positions of said throat plate and said prongs whereby the position of the throat plate may be adjusted relatively to the throat and said prongs may be retained in the desired position relative to the line composing devices.

2. A chute spring adapted to be secured in juxtaposition to the matrix chute of a type bar making machine embodying a throat plate for engaging the matrices as they pass through the throat, forwardly extending prongs arranged to prevent the matrices from jumping upwardly from the line forming position, the lower end of said throat plate extending down below the under side of said prongs whereby the tops of the matrices will move from contact with the throat plate to a vertical position without interference by said prongs.

3. A chute spring adapted to be secured in juxtaposition to the matrix chute of a type bar making machine, embodying a throat plate for engaging the matrices as they pass through the throat, forwardly extending prongs arranged to prevent the matrices from jumping upwardly from the line forming position, a stop pin for coöperating with a portion of the magazine plate of said machine to limit the movement of said throat plate toward the matrix chute, and means for adjusting the position of the said stop pin on said spring whereby the said prongs may be arranged at different heights relative to the stop pin.

4. A device of the character described in a type bar making machine, comprising a depending chute spring having a throat plate 8, arranged near the throat of said ma-

- chine and adapted to engage the matrices passing therethrough, a member secured near the lower end of said chute spring and having laterally extending prongs adapted 5 to prevent the matrices from jumping out of the line forming position, said throat plate extending below the said prongs, and adjustable means for holding the said throat plate and said prong member in separated relation for the purpose set forth.
5. A chute spring adapted to be secured in juxtaposition to the matrix chute of a type bar making machine, comprising a chute spring having a throat plate arranged 10 to contact with the matrices as they pass through the assembling throat of the machine, said throat plate having a forwardly curved lower end, and a member having forwardly extending prongs arranged to prevent the matrices from jumping upwardly from the line forming position, the said curved lower end of the throat plate extending below the under side of said prongs whereby the tops of the matrices will move from contact with the throat plate to a vertical position without interference by said prongs.
- 15 In testimony whereof I affix my signature in presence of two witnesses.
